RECOVERY OF LUBRICATING OIL FROM
ACID SLUDGEJudson Bruce Synott, Jr., Port Arthur, Tex., as-
signor to The Texas Company, New York, N. Y.,
a corporation of Delaware

Application May 10, 1938, Serial No. 207,001

6 Claims. (Cl. 196—148)

This invention relates to the recovery of lubricating oil from acid sludge derived from the treatment of petroleum lubricating oil with sulfuric acid.

5 The process of the invention is particularly useful in the recovery of lubricating oil from acid sludge derived from the treatment of residual lubricating oils. In the treatment of residual lubricating oils with sulfuric acid from 25% to 10 50% of the oil is ordinarily lost as acid sludge.

The process of the invention is also useful in the recovery of lubricating oil from acid sludge obtained in the treatment of distillate lubricating oils. In the treatment of distillate lubricating oils with sulfuric acid from 5% to 15% of the oil is usually lost as acid sludge.

In the past efforts to recover acid sludge have been directed more particularly to the recovery of acid from the sludge. Very little attention 20 has been given to the recovery of lubricating oil from acid sludge. It is common practice to dispose of acid sludge, after separation of a part of the contained acid, as a waste product.

I have discovered that a large part of the acid 25 sludge which is produced in the treatment of petroleum lubricating oil with sulfuric acid consists of valuable lubricating oil which can be recovered. It is an object of the invention to provide a practical method for recovering said valuable lubricating oil.

30 My invention concerns a method of recovering lubricating oil from acid sludge derived from the treatment of petroleum lubricating oil with sulfuric acid. According to the invention low boiling petroleum oil and water are added to the acid sludge and the following materials are separated from the sludge:

1. An acid oil consisting of a portion of the sludge dissolved in the low boiling petroleum oil.
2. An asphaltic material which is relatively insoluble in the low boiling petroleum oil.
3. Weak acid.

The acid oil above described is neutralized by 45 heating it to decompose and vaporize contained acid compounds and the acid vapors are separated from the oil. The neutralized oil is distilled and the low boiling petroleum oil is separated therefrom. Lubricating oil is recovered from the oil remaining after the separation of the low boiling petroleum oil.

50 The invention will be more fully understood by referring to the following description and the accompanying drawing.

The single figure of the drawing is a diagrammatic view in elevation of apparatus suitable for

recovering lubricating oil from acid sludge in accordance with the process of the invention.

In carrying out the process of the invention, a lubricating oil, which may be a distillate oil or a residual oil obtained from any type of crude oil, may be treated with sulfuric acid and the treated oil may be separated from the acid sludge. If desired the acid sludge derived from the acid treatment of different types of lubricating oils may be segregated according to the type of oil treated, but for convenience and economy the acid sludge produced in the acid treatment of a plurality of lubricating oil stocks may be commingled and recovered in a single operation. It is contemplated that in most oil refining plants a composite lubricating oil sludge can be made available which will be of substantially uniform quality over a long period of time. The process of the invention can be carried out to best advantage as a continuous process.

The first step of the process comprises adding low boiling petroleum oil and water to the acid sludge and separating from the sludge an acid oil consisting of a portion of the sludge dissolved in the low boiling petroleum oil, an asphaltic material which is relatively insoluble in the low boiling petroleum oil, and weak acid. The low boiling petroleum oil may consist of a light gas oil, for example. A cycle gas oil of the type which is ordinarily obtained as a by-product of a cracking operation, in the manufacture of gasoline from oils of higher boiling point, and which, because of its refractory nature, is not economical to use as a cracking stock, is particularly suitable for use in the process of this invention.

The separation of the acid sludge which has been described in the preceding paragraph may be accomplished in stages if desired. The following example illustrates a method which may be employed in effecting this separation:

Referring to the drawing, the acid sludge may be mixed with from about 10% to about 15% of water and from about 75% to about 95% of low boiling petroleum oil, for example, and delivered to a vessel 1 through a pipe 2. In the vessel 1 the mixture may be heated in direct contact with steam introduced through a pipe 3 for about 5 hours, for example. The vessel 1 preferably is a closed vessel, so that the sludge mixture may be heated therein out of contact with air. A pressure ranging from atmospheric pressure to a pressure of about 100 pounds per square inch, for example, may be maintained on the mixture while it is being heated. Immediately following the heating step the sludge mixture may be allowed

to settle for about 5 hours, for example. The settling step also may be carried out in the vessel 1. An inert gas such as flue gas may be introduced into the vessel 1 during the settling step through a pipe 4 to provide a blanket which will protect the sludge mixture from contact with air. Upon settling the sludge mixture an acid oil consisting of a portion of the sludge dissolved in low boiling petroleum oil may be separated from the remainder of the sludge mixture. Said acid oil may be withdrawn from the vessel 1 thru draw-off pipes 5, 6 and 7 and delivered into a tank 8. The remaining sludge mixture may be mixed with about 25% of low boiling petroleum oil introduced thru a pipe 9, for example, and again heated in direct contact with steam for about 5 hours. It may be allowed to settle for about an hour, after which a portion of the weak acid contained therein may be separated from the sludge mixture. The heating and settling steps may be repeated one or more times and additional amounts of acid oil and weak acid may be separated from the sludge. Finally an asphaltic material may be recovered which is relatively insoluble in the low boiling petroleum oil. Preferably the heating and settling steps above described are carried out in vessels which are lined with a corrosion resistant material. The gases produced during the process should be treated to remove objectionable compounds therefrom before discharging them to the atmosphere.

The acid oil may be withdrawn from the tank 8 thru a pipe 10, by means of a pump 11. A valve 12, which is situated in the pipe 10, is provided for closing the pipe 10 in the event of an emergency. The pipe 10 discharges into the upper portion of a fractionating tower 13. The fractionating tower 13 preferably is lined with an acid resistant material such as acid brick. The acid resistant lining is indicated by the numeral 14. Contacting devices such as the baffles 15 may be provided in the tower 13. The acid oil is passed downwardly in the tower 13 and is heated by direct contact with hot vapors which are introduced into the lower portion of the tower 13 thru a pipe 16. The hot vapors are produced by heating a low boiling petroleum oil of the type above described, as will be explained more fully in the following remarks. The acid oil is thus heated to a temperature sufficiently high to decompose and vaporize contained acid compounds. Preferably a temperature of from about 400° F. to about 550° F. is maintained in the tower 13. The vaporized acid compounds may be separated from the acid oil and withdrawn from the tower 13 thru a pipe 17. The acid vapors may be condensed by means of a jet condenser 19. Water may be delivered to the jet condenser 19 thru a pipe 20. A valve 21, which is situated in the pipe 20, regulates the amount of water which is delivered to the jet condenser 19. A neutralizing agent such as sodium hydroxide may be introduced into the pipe 20 thru a pipe 22. A valve 23, which is situated in the pipe 22, regulates the amount of neutralizing agent which is delivered into the pipe 20.

The mixture of condensed acid vapors and water leaving the jet condenser 19 may be delivered into a water separator 24 thru a pipe 25. Water is withdrawn from the water separator 24 thru a pipe 27. A valve 28, which is situated in the pipe 27, is provided for disconnecting the water separator 24 from the pipe 27. Uncondensed gases may be withdrawn from the water sepa-

rator 24 thru a pipe 29. These gases should be treated to remove objectionable compounds therefrom before discharging them to the atmosphere.

The neutralized oil from which the acid vapors have been separated may be withdrawn from the tower 13 thru a pipe 31. The hot vapors which are delivered into the tower 13 thru the pipe 16 may be condensed by contact with the relatively cold oil which is introduced to the tower 13 thru the pipe 10. The low boiling petroleum oil produced by condensation of said vapors may be withdrawn from the tower 13 along with said neutralized oil.

The neutralized oil withdrawn from the tower 13 may be delivered to a heating coil 33 by means of a pump 34 which is situated in the pipe 31. The heating coil 33 is situated in a furnace 35. A burner 36 is provided for supplying heat to the heating coil 33. The oil may be heated in the heating coil 33 to a temperature of from about 500° F. to about 650° F., for example. The heated oil may be delivered into a fractionating tower 38 by means of a pipe 39.

Contacting devices such as the baffles 41 may be provided in the tower 38. Reflux liquid, which may consist of low boiling petroleum oil, may be introduced into the tower 38 thru a pipe 42. A valve 43, which is situated in the pipe 42, regulates the amount of reflux liquid which is delivered into the fractionating tower 38.

In the fractionating tower 38 substantially all of the low boiling petroleum oil contained in the oil mixture which is introduced into the tower 38 thru the pipe 39 may be vaporized and separated from the heavier oil which is associated therewith. Said heavier oil contains the lubricating oil which it is an object of this invention to recover. The low boiling petroleum oil vapors may be withdrawn from the tower 38 thru a pipe 44.

The low boiling petroleum oil vapors which are withdrawn from the tower 38, together with vaporized reflux liquid, may be delivered into a fractionating tower 46. The fractionating towers 13, 38 and 46 preferably are maintained under substantially atmospheric pressure. Contacting devices such as the baffles 47 may be provided in the tower 46. Reflux low boiling, which may consist of light petroleum oil, may be introduced into the tower 46 thru a pipe 48. The pipes 42 and 48 are supplied with reflux liquid by a common supply pipe 49. A valve 50, which is situated in the pipe 48, regulates the amount of reflux liquid which is delivered into the fractionating tower 46.

In the fractionating tower 46 substantially all of the low boiling petroleum oil vapors withdrawn from the tower 38 may be condensed. Uncondensed gases may be withdrawn from the tower 46 thru a pipe 51. These gases preferably are treated to remove objectionable compounds therefrom before discharging them to the atmosphere.

The low boiling petroleum oil which is condensed in the tower 46 may be withdrawn from the tower 46 thru a pipe 53. A valve 53, which is situated in the pipe 53, regulates the amount of low boiling petroleum oil which is withdrawn from the tower 46. A part of the low boiling petroleum oil withdrawn from the tower 46 may be delivered to a heating coil 54 by means of a pump 55. The heating coil 54 is situated in a furnace 56. A burner 57 is provided for supplying heat to the heating coil 54. A valve 58, which is situated in the pipe 53, regulates the

amount of low boiling petroleum oil which is delivered to the heating coil 54.

The low boiling petroleum oil may be heated in the heating coil 54 to a temperature of from about 700° F. to about 900° F., for example, and delivered into the tower 13 thru the pipe 16. The low boiling petroleum oil enters the tower 13 as a vapor and is used to heat the acid oil which is delivered into the tower 13 thru the pipe 10.

10 Said low boiling petroleum oil preferably is of a type that is not easily decomposed upon heating. It is not maintained at high temperatures for sufficient time to effect an appreciable amount of cracking or decomposition thereof.

15 A part of the low boiling petroleum oil withdrawn from the tower 46 may be diverted from the pipe 53, thru a by-pass pipe 60, and passed thru a cooling coil 61 which is situated in a water box 62. A valve 64, which is situated in the 20 by-pass pipe 60, regulates the amount of low boiling petroleum oil which is passed thru the cooling coil 61.

25 The low boiling petroleum oil leaving the cooling coil 61 may be delivered into an accumulator drum 65. It may be withdrawn from the accumulator drum 65 thru the pipe 49, by means of a pump 66. Part of the low boiling petroleum oil withdrawn from the accumulator drum 65 may be delivered by the pipe 49, thru the branch 30 pipes 42 and 48, to towers 38 and 46, respectively, to be used as reflux therein. The remainder may be discharged from the system thru a branch pipe 67. A valve 68 in the branch pipe 67 regulates the amount of low boiling petroleum oil which is 35 discharged from the system. The low boiling petroleum oil which is discharged from the system may be used again in the process, for separating a fresh supply of acid sludge.

40 A relatively heavy oil may be withdrawn from the tower 38 thru a pipe 69. This oil contains the lubricating oil which it is an object of this invention to recover. A valve 70, which is situated in the pipe 69, regulates the amount of said heavy oil which is withdrawn from the tower 38.

45 The heavy oil withdrawn from the tower 38 may be delivered to a heating coil 71 by means of a pump 72. The heating coil 71 is situated in a furnace 74. A burner 75 is provided for supplying heat to the heating coil 71. The heavy oil may be heated in the heating coil 71 to a 50 temperature of from about 650° F. to about 800° F. and delivered into a fractionating tower 76 thru a pipe 77. An alkali such as sodium hydroxide may be introduced into the heated oil which is moved thru the pipe 77 by means of a branch pipe 79 which is connected to the pipe 77. A valve 80, which is situated in the pipe 79, regulates the amount of alkali which is delivered into the pipe 77.

55 A pressure less than atmospheric preferably is maintained in the fractionating tower 76. Steam may be introduced into the tower 76 thru a pipe 81. A valve 82, which is situated in the pipe 81, regulates the amount of steam which is delivered to the tower 76.

60 Contact devices such as the baffles 83 may be provided in the tower 76. Reflux liquid, which may consist of water, may be delivered to the tower 76 thru a pipe 84. A valve 85, which is situated in the pipe 84, regulates the amount of reflux liquid which is delivered to the tower 76.

65 Trap trays 86 and 87 are provided in the fractionating tower 76 for collecting and withdrawing distillate lubricating oils which may be separated from the heated oil. Said distillate lu-

bricating oils may be withdrawn from the trap trays 86 and 87 thru pipes 88 and 89, by means of pumps 90 and 91, respectively, which are situated in said pipes. The distillate lubricating oils withdrawn from the trap trays 86 and 87 may be 5 passed thru cooling coils 92 and 93, which are situated in water boxes 94 and 95, and discharged from the system.

70 The heavy oil withdrawn from the tower 38 may contain emulsifying constituents, including 10 certain organic acids, which are undesirable in a finished lubricating oil. These compounds may be converted into soaps by causing them to react with the alkali which is introduced into the pipe 77. The resulting organic acid soaps may be 15 separated by distillation in the tower 76 to produce distillate lubricating oils which are substantially free of emulsifying constituents. The organic acid soaps may be separated from the residual oil by extraction with a liquefied normally 20 gaseous hydrocarbon such as propane.

25 The distillate lubricating oils which are withdrawn from the tower 76 may be further refined, for example, by treatment with a solvent such as furfural, treatment with sulfuric acid, neutralizing and decolorizing by treatment with adsorbent clay, and dewaxing.

30 A residual lubricating oil may be withdrawn from the tower 76 thru a pipe 96, by means of a pump 97. A valve 98, which is situated in the 35 pipe 96, regulates the amount of residual oil which is withdrawn from the tower 76. The residual lubricating oil withdrawn from the tower 76 may be passed thru a cooling coil 99, which is situated in a water box 100, and discharged from the system.

35 The residual lubricating oil which is withdrawn from the tower 76 may be further refined by treatment with a liquefied normally gaseous hydrocarbon such as propane, to separate therefrom contained asphaltic compounds and organic acid soaps. It may then be refined, for example, by treatment with sulfuric acid, neutralizing and decolorizing by treatment with adsorbent clay, and dewaxing. The asphaltic compounds which 40 are separated from said residual oil, and which may contain a considerable amount of organic acid soaps, may be recovered and used in the manufacture of emulsified asphalts.

45 A small amount of low boiling petroleum oil 50 may be recovered from the heated oil which is delivered to the fractionating tower 76. Said low boiling petroleum oil, together with vaporized reflux liquid, may be withdrawn from the tower 76 as a vapor, thru a pipe 101. The low boiling petroleum oil vapors withdrawn from the tower 76 may be 55 condensed by passing them thru a heat exchanger 103 in which they are cooled by indirect contact with a cooling fluid which is delivered to the heat exchanger 103 by a pipe 104 and withdrawn therefrom thru a pipe 105. The condensed vapors may be withdrawn from the heat exchanger 103, thru a pipe 107 and delivered into fractionating tower 108. Reflux liquid, which may consist of water, may be delivered into the 60 tower 108 thru a pipe 110. A valve 111, which is situated in the pipe 110, regulates the amount of reflux liquid which is delivered into the fractionating tower 108.

65 Contact devices such as the baffles 112 may be provided in the fractionating tower 108. The condensed low boiling petroleum oil may be withdrawn from the fractionating tower 108 thru a pipe 113, by means of a pump 114. A valve 115, which is situated in the pipe 113, regulates the amount of low boiling petro- 70 75

leum oil which is withdrawn from the fractionating tower 108.

Uncondensed gases, together with vaporized reflux liquid, may be withdrawn from the fractionating tower 108 thru a pipe 116. Said uncondensed gases and vaporized reflux liquid are delivered to a barometric condenser 118. Water may be delivered to the barometric condenser 118 thru a pipe 119. A valve 120, which is situated in the pipe 119, regulates the amount of water which is delivered to the barometric condenser 118. A portion of said gases and vaporized reflux liquid may be condensed by the barometric condenser and withdrawn thru the tail pipe 123. The gases which are not condensed by the barometric condenser 118 may be withdrawn by a vacuum pump 121 which is provided for the purpose of maintaining a partial vacuum in the fractionating towers 76 and 108.

Obviously many modifications and variations of the invention as hereinbefore set forth may be made without departing from the spirit and scope thereof and only such limitations should be imposed as are indicated in the appended claims.

I claim:

1. The method of recovering lubricating oil from acid sludge derived from the treatment of petroleum lubricating oil with sulfuric acid which comprises adding low boiling petroleum oil and water to the acid sludge, separating from the sludge an acid oil consisting of a portion of the sludge dissolved in the low boiling petroleum oil, an asphaltic material which is relatively insoluble in the low boiling petroleum oil, and weak acid neutralizing the acid oil by heating it to decompose and vaporize contained acid compounds, separating the acid vapors, distilling the neutralized oil and separating therefrom the low boiling petroleum oil, and recovering lubricating oil from the oil remaining after the separation of the low boiling petroleum oil.

2. The method of recovering lubricating oil from acid sludge derived from the treatment of petroleum lubricating oil with sulfuric acid which comprises adding low boiling petroleum oil and water to the acid sludge, separating from the sludge an acid oil consisting of a portion of the sludge dissolved in the low boiling petroleum oil, an asphaltic material which is relatively insoluble in the low boiling petroleum oil, and weak acid, neutralizing the acid oil by heating it to decompose and vaporize contained acid compounds, separating the acid vapors, distilling the neutralized oil and separating therefrom the low boiling petroleum oil and a distillate lubricating oil.

3. The method of recovering lubricating oil from acid sludge derived from the treatment of petroleum lubricating oil with sulfuric acid which comprises adding low boiling petroleum oil and water to the acid sludge, separating from the sludge an acid oil consisting of a portion of the sludge dissolved in the low boiling petroleum oil, an asphaltic material which is relatively insoluble

in the low boiling petroleum oil, and weak acid, neutralizing the acid oil by heating it to decompose and vaporize contained acid compounds, separating the acid vapors, distilling the neutralized oil and separating therefrom constituents of low boiling point, and recovering lubricating oil from the oil remaining after the separation of the low boiling point constituents.

4. The method of recovering lubricating oil from acid sludge derived from the treatment of petroleum lubricating oil with sulfuric acid which comprises adding low boiling petroleum oil and water to the acid sludge, separating from the sludge an acid oil consisting of a portion of the sludge dissolved in the low boiling petroleum oil, an asphaltic material which is relatively insoluble in the low boiling petroleum oil, and weak acid, neutralizing the acid oil by heating it to decompose and vaporize contained acid compounds, separating the acid vapors, distilling the neutralized oil under substantially atmospheric pressure and separating therefrom the low boiling petroleum oil, distilling the remaining oil under less than atmospheric pressure and separating therefrom a distillate lubricating oil.

5. The method of recovering lubricating oil from acid sludge derived from the treatment of petroleum lubricating oil with sulfuric acid which comprises adding low boiling petroleum oil and water to the acid sludge, separating from the sludge an acid oil consisting of a portion of the sludge dissolved in the low boiling petroleum oil, an asphaltic material which is relatively insoluble in the low boiling petroleum oil, and weak acid, neutralizing the acid oil by heating it to decompose and vaporize contained acid compounds, separating the acid vapors, distilling the neutralized oil under substantially atmospheric pressure and separating therefrom the low boiling petroleum oil, distilling the remaining oil under less than atmospheric pressure and in the presence of an alkali, and separating therefrom a distillate lubricating oil which is substantially free of emulsifying constituents.

6. The method of recovering lubricating oil from acid sludge derived from the treatment of petroleum lubricating oil with sulfuric acid which comprises adding low boiling petroleum oil and water to the acid sludge, separating from the sludge an acid oil consisting of a portion of the sludge dissolved in the low boiling petroleum oil, an asphaltic material which is relatively insoluble in the low boiling petroleum oil, and weak acid, neutralizing the acid oil by heating it to decompose and vaporize contained acid compounds, separating the acid vapors, distilling the neutralized oil under substantially atmospheric pressure and separating therefrom the low boiling petroleum oil, distilling the remaining oil under less than atmospheric pressure and separating therefrom constituents of low boiling point, and recovering lubricating oil from the oil remaining after the separation of the low boiling point constituents.

JUDSON BRUCE SYNNOTT, JR.
